DESIGN FOR A LADY'S CAP

Harry Harnick and Joseph Saslow, Brooklyn, N. Y.

Application January 27, 1938, Serial No. 74,586

Term of patent 3½ years

To all whom it may concern:

Be it known that we, Harry Harnick, and Joseph Saslow, both citizens of the United States, and residents of Brooklyn, New York, in the the county of Kings and State of New York, have invented a new, original, and ornamental Design for a Lady's Cap, of which the following is a specification, reference being had to the accompanying drawing, forming a part thereof:

Fig. 1 is a perspective view of a lady's cap, showing my new design.

Fig. 2 is a front elevational view of same.

Fig. 3 is a developed view of same.

We claim:

The ornamental design for a lady's cap, as shown.

HARRY HARNICK.
JOSEPH SASLOW.
